UNITED STATES PATENT OFFICE

ISAAC APPELBAUM, OF PHILADELPHIA, PENNSYLVANIA

FOLDING BOX OR CONTAINER

Application filed April 13, 1927. Serial No. 183,365.

My invention relates to a novel construction of a folding box or container and comprises a novel construction of blank having side flaps, locking tabs, a hanger flap and a handle arranged and collocated in a novel manner with respect to each other and to the body of the blank, whereby when the blank is folded as hereinafter described, a very neat, compact and durable folding box or container is produced which is securely held in assembled position, and which can be utilized not only as a carrier for ladies' garments and other apparel or the like, but can also be used to hold such apparel suspended in a closet or the like.

It further consists of a novel construction of a folding box or container having a hanger flap, side flaps and a handle on one portion of the blank from which the container is formed, the other portion of the blank being provided with locking tabs, and a novel construction and arrangement of creases whereby my novel box or container is produced.

It further consists of other novel features of construction and advantage, all as will be hereinafter pointed out in the specification and claims appended hereto.

For the purpose of illustrating my invention, I have shown in the accompanying drawings forms thereof which are preferred by me since they will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a plan view of a blank from which my novel construction of folding box or container is produced.

Figure 2 represents a perspective view showing the folding box or container in partly folded condition.

Figure 3 represents a side view of the completed box or container.

Figure 4 represents a section on the line 4-4 Figure 3.

Similar numerals of reference indicate cor-

responding parts in the figures. Referring to the drawings.

In carrying out my invention I employ a novel construction of blank of substantially the contour seen in Figure 1, said blank being composed of the body portions 2 and 3 which are formed by the transverse scorings or creases as indicated by the parallel dotted lines 4 and 5. The parallel longitudinally extending lines 6 indicate longitudinal creases or scorings which are continued to form the creases or scorings 7 which form the boundary for the body portion 2, said creases or scorings 6 forming the outer boundary for the body portion 3. The dotted lines 8 represent a pair of outer creases or scorings which are parallel with the lines 6 and serve to form the side flaps 9 having the ends 10 which are coincident with the transverse creases 5 and the ends 11 which are coincident with the outer right hand crease or scoring 12.

13 designates the end flap which has the cut out portion 14 which when the blank is laid out flat incloses the handle member 15 as will be understood from the right hand portion of Figure 1. The outer edges 16 of the body portion 2 are coincident with the parallel creases or scorings 8 and form the outer sides of the body 2 which latter at the left hand portion is provided with the parallel creases or scorings 17 and 18. The side locking tabs for the body portion 2 are indicated at 19, and the end locking tabs which are preferably three in number are indicated at 20 and 21, the two outer tabs being indicated at 20, and the inner or central tab being indicated at 21. When the blank is folded in the operative position, the side flaps 9 assume the position seen in Figure 2, and the hanger flap 13 is folded inwardly as seen in Figure 2, leaving the handle 15 standing as seen in said figure. The central locking tab 21 engages the central slot 22, and the two outer end locking tabs 20 engage the slots 23. The inner locking tabs 19 engage the slots 24, and the outer locking tabs 19 engage the outer slots 25.

It will be apparent that when the side flaps 9 are bent as indicated in Figure 2, a well defined wall 26 will be formed between the scor-

ings 6 and 8, and the capacity of the box or container can be readily increased or diminished according to requirements. Between the scorings 17 and 18, seen at the left of Figure 1, a well defined wall 27 is formed which forms the top of the box or container when the same is closed, as will be understood from Figure 4.

It will also be noted that the space 30 between the scorings 4 and 5 serves as the bottom for the container when the blank is bent into the position seen in Figure 4.

If desired a transverse retaining strip as indicated at 28, in Figures 1, 2 and 4 may be employed, said strip being of paper, card-board, cloth or other material, and serves to hold a garment 29 contained within the container nicely in folded position. It will be understood that the blank 1 can be composed of any suitable material as paper of the requisite thickness, card board or the like, and the same can be impregnated with any suitable material such as a suitable germicide or insecticide which will be offensive to moths, insects or other vermin. If desired, the blank 1 can be made of tarred paper or the like, and the handle 15 affords a convenient means for carrying the device, and the articles of apparel can be left in the latter, and the container suspended in open or closed condition from the handle 15 in a closet or the like, if desired.

It will be apparent that when the edges 16 of the body portion 2 are folded inwardly on the lines 7, well defined side flanges 30 are formed which fold against and enclose the walls 26, as will be understood from Fig. 3, so that the contents of the container are adequately closed and protected on all four sides.

It will now be apparent that I have devised a novel and useful construction which embodies the features of advantage enumerated as desirable in the statement of the invention and the above description, and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:

1. A blank of the character described, consisting of two body portions, divided by transverse central scorings, whereby a base is formed, one of said body portions being provided with opposed side flaps, each flap being separated from its body portion by a pair of parallel scorings, forming side walls of a predetermined height, an end hanger flap, side and end locking tabs on the opposite

body portion, the latter being scored to form side flanges and a top portion adapted to enclose the sides and top of the opposed body portion when said body portions are folded.

2. A blank of the character stated, consisting of two body portions, divided by transverse central scorings, whereby a base is formed, one of said body portions being provided with opposed side flaps, each flap being separated from its body portion by a pair of parallel scorings, forming side walls of a predetermined height, an end hanger flap, a handle member for said blank, and side and end locking tabs on the opposite body portion, the latter being scored to form side flanges and a top portion adapted to enclose the sides and top of the opposed body portion, when said body portions are folded.

3. A blank for a container of the character described, consisting of two body portions, divided by transverse central scorings, whereby the base of the container is formed, one of said body portions being provided with opposed side flaps, each flap being separated from its body portion by a pair of parallel scorings forming end walls of a predetermined height, an end hanger flap, a handle member positioned within said hanger flap, side and end locking tabs on the opposite body portion, the latter having side flanges, and a top portion adapted to enclose the sides and top of the opposed body portion.

4. A blank for a container of the character described, consisting of two body portions, divided by transverse central scorings, whereby a base is formed, one of said body portions being provided with opposed side flaps, each flap being separated from its body portion by parallel scorings forming side walls of a predetermined height, an end hanger flap, side and end locking tabs on the opposite body portion, the latter being scored to form side flanges and a top portion adapted to enclose the sides and top of the opposed body portion when said body portions are folded, and a transverse strip on the body portion containing the locking tabs for retaining a garment in position.

5. A container of the character stated comprising two integral body portions adapted to be folded against each other, a handle integral with the end of one of said body portions, an end hanger flap integral with the end of said body portion, the opposite integral body portion having side flanges, and side locking tabs formed thereon, said last mentioned body portion also having a top flap formed thereon and being provided with a plurality of end locking tabs and a transverse hanger member, said tabs engaging slots in the opposite body portion.

6. A container of the character stated comprising two integral body portions adapted to be folded against each other, an end hanger flap integral with one of said body portions,

the opposite integral body portion having side flanges, side and end locking tabs, and a top flap formed thereon, said tabs being adapted to engage slots in the opposite body portion, to lock said body portions in the folded condition to form a container.

7. A folding container of the character stated formed of a blank having a pair of transverse creases therein, whereby two side walls and an intermediate base are formed, said side walls being adapted to be folded against each other to form a container, a hanger flap integral with the end of one of said side portions, outer longitudinal parallel creases at the outer portions of one of said side walls forming side flaps, inner longitudinal, parallel creases forming flanges for said side walls adapted to be folded inwardly with respect thereto to form end walls of predetermined width, and means for locking said side walls and said flaps in folded position.

8. A container of the character stated, comprising foldable integral juxtaposed panels, integral, longitudinal, foldable side flaps therefor, parallel, longitudinal creases forming side flanges for said panel, adapted to be folded to form side walls of predetermined width for said container when said panels are folded, a handle integral with the upper transverse edge of one of said side panels, and a plurality of side and end fastening tabs formed integrally with the edges of one of said panels and adapted to engage slots in the edges of the other of said panels to secure said side panels in folded condition.

9. A blank adapted to be folded to form a folding container, comprising juxtaposed, integral, foldable side panels connected by an intermediate base and adapted to form side walls for said container, foldable side flaps integral with the longitudinal edges of said side panels and adapted to form end walls for said container, a handle integral with the transverse edge of one of said side panels, and locking tabs carried by one of said side panels and adapted to engage slots in the other of said side panels when said blank is folded to form said container.

ISAAC APPELBAUM.
